UNITED STATES PATENT OFFICE

2,445,079

LAMP

Walter M. Petersdorf, Milwaukee, Wis.

Application May 26, 1947, Serial No. 750,415

1 Claim. (Cl. 240—10)

1

This invention appertains to electric lighting and more particularly to bedroom, living room and like lamps.

One of the primary objects of my invention is to provide a lamp embodying a suitable base and the usual electric light bulb stand, means incorporated directly with the base of said lamp for giving a low dim light for indicating the exact position of said lamp in a dark room, when the circuit to said usual light bulb is open.

Another salient object of my invention is to provide a lamp embodying a base for supporting the usual incandescent light bulb and shade, in the form of an animal or bird, with small glow bulbs in said base at the eyes of the simulated figure for not only indicating the position of the lamp, but to give an attractive and ornamental device.

A further important object of my invention is to provide a simple, inexpensive and convenient means for mounting the glow bulbs in the base of the lamp.

With these and other objects in view the invention consists in the novel construction, arrangement and formation of parts as will be hereinafter more specifically described, claimed and illustrated in the accompanying drawing, in which drawing

Figure 1 is a front elevational view showing a lamp constructed in accordance with my invention, the shade for the incandescent light bulb being shown in dotted lines.

Figure 2 is a vertical section view through the lamp taken substantially on the line 2—2 of Figure 4, looking in the direction of the arrows.

Figure 3 is an enlarged fragmentary vertical section view taken at right angles to Figure 2 and on the line 3—3 of Figure 1, looking in the direction of the arrows, the view illustrating, more particularly, the means employed for holding the glow bulbs in position.

Figure 4 is an enlarged horizontal sectional view taken on the line 4—4 of Figure 1 looking in the direction of the arrows.

Figure 5 is a diagrammatic view illustrating the wiring for the lamp.

Referring to the drawing in detail, wherein similar reference characters designate corresponding parts throughout the several views, the letter L generally indicates my improved lamp and the same includes a base 6 preferably in the form of an animal or bird. In the form of my invention illustrated, I have shown the base constructed to simulate the appearance of an owl and the head of the owl is provided with open-

2

ings 7 at the eyes thereof, for a purpose which will be later set forth. The head is also provided with an interior chamber 8 which opens out through the back of the base or figure. Associated with the base at the extreme upper end thereof is a nipple or standard 9 for an electric light bulb socket 10. The socket 10 can receive any preferred type of incandescent light bulb 11. The socket 10 can be provided with a switch 12. It is to be noted that the base is provided with a vertical passageway 13 for receiving the feed and return wires 14 and 15 for the light bulb. These wires extend out through a suitable lateral passageway 16 for connection with the usual house circuit.

The base 6 can carry a shade or reflector for the bulb 11 and as shown in dotted lines in Figure 1 a shade 17 is provided which is snapped on the light bulb 11.

20 The chamber 8 forms a compartment for receiving a companion pair of small glow lamps or bulbs 18 and 19. The bulbs are of a well known character generally employed as pilot lights, current indicators and the like, and one 25 well known type thereof is the bulb placed on the market by the General Electric Company, number "N. E. 2."

The glow lamps or bulbs 18 and 19 are carried by a partition wall 20 of cardboard or other insulating material and the wires from the lamps extend through openings 21 in the partition wall which holds the bulbs or lamps in place. The position of the lamps or bulbs 18 and 19 is such that when the wall is forced into the compartment 8, the bulbs will be in rear of the eye openings 7.

After the light bulbs 18 and 19 and their resistance elements 22 and 23 are placed in the chamber with the partition wall, a guard wall 24 can be placed in the chamber in rear of the partition wall 20 so as to form a guard for the electric wires 14 and 15. After the guard wall is placed in position plaster of Paris 25 or any like substance can be used to fill the balance of the compartment so that a solid structure will be had.

Referring to the wiring diagram it will be noted that the feed and return wires 14 and 15 lead to the terminals for the incandescent light bulb 11 and that a switch 26 can be incorporated in one of these wires. Leading off from the wire 14 are branch wires 27 and 28 and these wires lead respectively to one of the terminals for the glow lamps 18 and 19 and the other terminals 55 of the glow lamps have connected respectively

thereto branch return wires 29 and 30 which are electrically connected with the return wire 15. The resistance elements 22 and 23 can be connected in the length of the wires 27 and 28.

From the wiring diagram, it can be seen that whether the circuit is closed or open to the incandescent light bulb 11 that current will be supplied to the glow bulbs or lamps 18 and 19 and consequently light from these bulbs will be emitted through the eye openings 7 at all times. This will give a decorative effect and if the circuit is open to the light bulb 11, the glow lamps will indicate the position of the lamp in a dark room.

Changes in details may be made without departing from the spirit or the scope of my invention, but what I claim as new is:

A living room and like lamp comprising a base in the form of an animal or bird including a head having a hollow chamber therein and eye openings communicating with said chamber, an electric light lamp socket carried by said base, electric feed and return wires for said socket extending through the chamber, glow lamp bulbs disposed in said chamber directly in rear of the

eye openings and electrically connected at all times with the feed and return wires, a partition wall disposed in said chamber for supporting the bulbs, a guard wall positioned in said chamber and forming a compartment with said partition wall for the wires for the socket, and means for filling the compartment in rear of the guard wall.

WALTER M. PETERSDORF.
